UNITED STATES PATENT OFFICE.

ARTHUR L. STANFORD, OF FORT HILL, ILLINOIS.

WOOD-CUTTING MACHINE.

SPECIFICATION forming part of Letters Patent No. 324,603, dated August 18, 1885.

Application filed July 15, 1884. (No model.)

To all whom it may concern:

Be it known that I, ARTHUR L. STANFORD, a citizen of the United States, residing at Fort Hill, in the county of Lake and State of Illinois, have invented a new and Improved 5 Wood-Cutting Machine; and I hereby declare the following to be a full, clear, and exact description of the same.

My invention relates to a machine chiefly adapted for cutting green wood into short 10 lengths for fire-wood. My machine operates on a principle which, so far as I am aware, has never before been utilized for the same or any analogous purpose. This principle 15 consists in bending the timber at the point where it is to be severed, thus straining the fibers at that point, and reducing greatly the lateral pressure on the cutting-tool, and then forcing down upon it the edge of the cutting- 20 tool.

To carry my invention into effect, I employ a massive frame to rest upon the ground, provided with an adjustable beam at one end, under which the pole to be cut is slid over a 25 roller; a beam at the opposite end, under which the end of the pole passes, this beam being pivoted at one of its ends to a corner of the frame, and preferably counterbalanced outside the pivotal point, whereby the tendency of the opposite end is to rise, unless otherwise acted on; a block intermediate between the two beams, over which the pole is bent by forcing down the free end of the second beam; a knife above and a little to one 30 side of the block, pivoted at one end to the edge of the frame, and preferably counterbalanced beyond the pivotal point, whereby the tendency of the free end is to rise, unless otherwise acted on; and a system of friction- 35 clutches and levers for operating the same, whereby when the pole is slid into position the free end of the second beam is forced downward to bend it over the block, and the free end of the knife is likewise forced downward to sever it at the point of bending. 45

My invention consists in the general features above outlined, and also in certain details of construction and combinations of parts, all as hereinafter more fully set forth.

50 In the drawings, Figure 1 is a perspective view of my machine; Fig. 2, a central longi-

tudinal section of the same; Fig. 3, a side elevation showing the construction at the reverse side of Fig. 1; Fig. 4, an enlarged detail view of the friction-clutch mechanism 55 employed for the knife and bending-beam; Fig. 5, a central section of one of the friction-clutches; Fig. 6, a similar view of a modification of the same, and Fig. 7 a side elevation of the last. 60

The friction-clutch mechanism referred to above is applicable to various purposes, and forms the subject of a separate application for a patent.

A is the frame, rectangular in form, and of 65 either the construction shown or of any other that will give it the requisite strength and stability. I commonly form it of four planks or timbers, t t' t^2 , fitted together in the form of a rectangle, the timbers t' being mortised to 70 the timbers t and t^2 , which project beyond the planks t' at three corners of the frame, as shown at s . The timber t^2 is made considerably lower than the others, to permit the bending down of the forward end of the pole 75 which is to be cut. A plank, r , is bolted to the under sides of the timbers t' , and extends across the center of the frame, projecting at each end beyond the same, and a second plank, r' , extends similarly across the frame at the 80 end adjacent to the timber t^2 , projecting beyond the frame at one end, as shown. The frame is mounted on legs to bring it a sufficient height above the ground for convenience to the operator, and these legs are braced by 85 cross-pieces q . The side and end timbers, moreover, are braced by tie-rods p , extending through them and across the frame in both directions, and secured upon both sides of the timbers by nuts o . Across the top of the 90 frame, above the plank r , is a heavy timber, n , to the upper side of which an iron block, m , is bolted. At the nearer end of the frame a roller, l , is attached by bearings secured to the timber t , near the upper edge of the same, 95 to facilitate the pushing forward of the pole or sapling B which is to be cut.

Above the timber t is an adjustable bearing-beam C, under which the pole B is slid, and which prevents the pole from flying upward 100 when the farther end is bent down by the bending-beam D. The beam C is pivoted at its

end opposite the operating-levers to a **U**-shaped bearing, E, which fits as a yoke upon the projecting end of the timber t, and is bolted thereto. At the other end it is connected to a friction-clutch, F, the friction-clutch being pivoted to a bearing, k, secured to each side of the beam. The construction of this friction-clutch corresponds with those which operate the bending-beam and knife, and will be fully described farther on. The friction-clutch F slides on a metal bar, G, the lower end of which is provided with an eye and rests within a mortise formed in the projecting end of the timber t. A **U**-shaped bearing, E', fits upon and is bolted to this end of the timber also, and the upper bolt passes through the eye of the bar G, whereby the said bar may vibrate as an inverted pendulum.

The knife H is pivoted at its end opposite the operating-levers to a bearing, E², secured at its lower end to the projecting end of the plank r, and at its free end the knife moves within a guide, I, which may be conveniently formed of a **U**-shaped iron bar bolted to the top of the frame, as shown, and which causes the knife to descend close to the block m.

The bending-beam D is pivoted at the end opposite the operating-levers to a **U**-shaped bearing, E³, which fits upon the projecting end of the timber t², and is bolted thereto. The beams C and D and the knife H are all counterbalanced by weights K, attached to extensions L at their pivoted ends, whereby their opposite ends will tend upward of their own accord on being liberated.

It now remains to describe the mechanism by which the beam C is rendered adjustable to graduate the space intervening between it and the timber t according to the thickness of the pole to be passed through this space; also that by which the beam D is brought down upon the end of the pole to bend it over the block m and released at will, and also that by which the knife H is brought down upon the pole at the point of bending and released at will. The mechanism which operates the bending-beam and the knife are substantially identical, and therefore a description of the former will serve for both.

Upon reference to Fig. 1 it will be seen that a bar, G', similar in all respects to the bar G, already described, is pivoted at its lower end within a mortise formed in the projecting portion of the plank r', and extends up through a slot formed in the beam D near its end. Upon this bar, below the beam, are two friction-clutches, the upper one, M, being suspended to the beam by means of stirrups i, and the lower one, M', being pivoted at its center to the forked end k' of a lever, N. In the fork near the clutch is a cross-bar, h, by which the lever is suspended to the beam D through the medium of a rod, i'.

The construction of the friction-clutches M and M' is such that when allowed to act normally they will readily slide downward upon the bar G', but will resist any attempt to slide

them upward. The upper clutch, M, constitutes what may be termed the "retaining-clutch," to hold the beam D down while the clutch M' is being lowered for a fresh grip. Without the retaining-clutch the bent pole B would operate by its elasticity to throw the beam upward whenever the pressure upon the lever N should be relaxed. The requisite conditions being established, however, as above outlined, the carrying down of the bending-beam D becomes a simple matter, for it will readily be seen that a downward pressure upon the lever N causes it to press upward upon the clutch M', in which direction it cannot move, and through the medium of the rod i' draws the beam D downward, and with it the clutch M, which, as explained, moves freely in this direction. Upon relaxing pressure on the lever the retaining-clutch catches upon the bar, owing to the upward pressure of the bent pole B, and by raising the lever the clutch M is lowered for a fresh grip; hence it will be seen that by working the lever up and down the bending-beam D is brought down by intermittent stages.

When the pole has been cut, it becomes necessary to raise the beam D for a fresh operation, and for this purpose the friction-clutches must for the time being be divested of their gripping tendency. Mechanism is provided whereby this is readily done, thus permitting the counter-balance K to throw the beam upward to its normal position.

A detailed description of the forms of friction-clutch which I prefer to employ, and also of the releasing mechanism just referred to, is as follows: As before stated, however, this clutch forms the subject of another application for a patent, and hence it is not separately claimed in this application. Each clutch M M' consists of a hollow rectangular body having the inner surface of its end walls, g, beveled, whereby at the bottom they are nearer the bar on which the clutch slides than at the top. Thus when the clutch is on the bar there is a space on each side of it in the form of a truncated wedge. At each end of the interior of the hollow body a roller, O, is mounted on journals f, projecting from the ends of the rollers through slots e, formed in the side walls of the body parallel with the inner surfaces of the end walls, g. Thus when the bar is passed through the opening d, formed centrally through the hollow body of the clutch, it has a roller at each side of it, which, seeking its lowest point through gravity, is normally in contact with both the bar and the end wall g adjacent to it. Hence the clutch is free to move downward on the bar, since any movement in this direction causes the rollers to ascend in the wedge-shaped chamber, and thus relax their pressure against the bar; but any attempt to move the clutch upward upon the bar causes the rollers to descend in the wedge-shaped chamber and grip the bar, and it is obvious that

the greater the upward pressure exerted upon the clutch the firmer its hold will become.

The construction shown in Fig. 5 is the simpler one; but in cases where the strain upon the clutch is considerable it can only be used with a hard-steel bar, since if the bar is of softer metal it is liable to be indented by the roller.

The modification shown in Figs. 6 and 7 provides for the use of a soft-metal bar, steel blocks P being interposed between the rollers O' and the bar. These blocks are less in height than the interior of the hollow body of the clutch, and are provided at their sides with pins f', passing through inclined slots e' in the body of the clutch. The purpose of thus mounting the blocks is to permit the operation of the releasing mechanism, about to be described, and for the same reason the rollers O', the inner surfaces of the walls g, and the sides of the blocks adjacent to the rollers are all fluted, and thus geared together. For a round bar the inner faces of the blocks may be curved.

Connected loosely to the journal f of the rollers O, or to the pins f' of the blocks P, when the modification shown in Figs. 6 and 7 is employed, and on each side of the body of the clutch, is a V-shaped attachment, Q, composed of two bars, c, loosely pivoted together at their lower ends. The same rivet which forms this pivot connects to the V-shaped attachment Q a forked lever, R, which passes around the end of the clutch, and is fulcrumed to it at the sides, as shown at b. Thus any downward pressure upon the outer end of the lever R raises the V-shaped attachments Q, and hence the rollers or blocks, as the case may be, which are immediately connected to it. If the form shown in Figs. 6 and 7 be the one employed, the raising of the blocks turns the rollers easily, by reason of the gear construction already described.

To press the ends of the levers R down, when desired, by operating from the end of the lever N, I employ the device comprising the bearing S, loosely suspended from the lever N, near its outer end, hand-plate, T, extending from this bearing nearly to the end of the lever, rod U, connecting the lower end of the bearing with the lower arm of a bell-crank lever, V, which is pivoted at its fulcrum to a fixed bearing, S', on the lever N, near the clutch M', and has its upper arm resting on the end of the lever R of that clutch, and wire V', connecting the rod U with the end of the lever R of the clutch M, and passing under the cross-piece h. When it is desired to release the clutch, it is only necessary to grasp the hand-plate T and press it against the lever. This throws the bearing S backward toward the end of the lever, pulling the rod U in the same direction, and thus bearing the levers R down through the medium of the bell-crank lever V and wire V'.

The knife H is operated, as before stated, by mechanism in all leading particulars identical with the foregoing, the friction-clutches

being mounted upon a bar, G', pivoted at its lower end to the plank r, and being operated by a lever, N'. If preferred, however, the knife may be operated by a single clutch, rendering it more stable by having the two parts for attachment to it lower than the portion which comes into contact with the wood to be cut. However, if the retaining-clutch be dispensed with, it is obvious that the counter-balance K upon the knife must be omitted and the knife lifted by hand, instead of automatically.

The end of the beam C may easily be lowered, in opposition to the counter-balance K, by simply moving the clutch F downward upon the bar G. To permit the sliding of this clutch upward to raise the beam, the lever R upon it must be pressed down, the construction of this clutch being, as before stated, in all respects identical with those already described.

The under side of the bending-beam D is provided with teeth a, to prevent the wood B from rolling or sliding to one side when the beam bears upon it in an inclined position.

The shape of the knife H is preferably curved, as shown, in order that it shall have no tendency to slide the pole to one side in its descent, and shall perform, to some extent, a draw-cut.

The friction-clutches which I have described are applicable to all purposes for which devices of that character are employed—such as for lifting jacks, stump-extractors, and the like. In most other applications, however, the support for the clutches, corresponding with the beam D, would be rigid and the bar movable. The releasing of the clutches would then cause the bar to fall. All this is fully explained in my application for a patent upon the friction-clutch alone. On the other hand, while this form of clutch is peculiarly well adapted to my wood-cutting machine, it is not an essential requisite, since other forms of clutch performing similar functions may be substituted for it.

The foregoing specification describes the mechanism which I prefer to employ for carrying my invention into effect. It is obvious, however, that changes may be made in the various operative parts (other parts as well as the clutches) without departing from the spirit of my invention. The essential features of the machine are a suitable supporting-frame, mechanism for bending the wood at the point where it is to be cut, and mechanism for cutting it at the point of bending, and my claims are intended to comprehend this general construction irrespective of matters of mere detail.

What I claim as new, and desire to secure by Letters Patent, is—

1. In a machine for cutting wood, the combination, with a supporting-frame provided with a bearing over which the wood is to be bent at the point where it is to be cut, of a beam toward one end of the frame, under which

the wood is passed, a vertically-movable beam toward the opposite end of the frame for bending the wood down over the bearing, a vertically-movable knife close to the bearing, and mechanism for operating both the bending-beam and knife, all substantially as described.

2. In a machine for cutting green wood, the combination of the following elements: a supporting-frame, a beam at one end of the frame, under which the wood is passed, a block intermediate between the ends of the frame, over which the wood is passed, a beam crossing the other end of the frame, under which beam also the wood passes, said beam being pivoted at one end to the frame, whereby by pressing down its opposite end the wood is bent over the block, a knife crossing the frame near the block, under which knife also the wood passes, said knife being pivoted at one end to the frame, whereby the forcing down of its opposite end causes it to cut the wood at the point of bending, and mechanism for forcing down the free ends of the bending-beam and knife, all substantially as described.

3. In a machine for cutting green wood, the combination of the frame A, adjustable beam C, block m, bending-beam D, pivotally connected at one end to a corner of the frame, and provided with a counter-balance, L K, 30 bar G, pivoted at its lower end to a bearing attached to the frame and passing through a mortise in the bending-beam, friction-clutch M on the bar G, connected to the beam D, friction-clutch M' on the bar G', below the 35 clutch M, lever N, connected at its end to the clutch M', rod i, connecting the lever N with the beam D, mechanism for releasing the clutches M and M', whereby they may be moved upward on the bar, knife H, pivotally connected to one side of the frame, and clutch mechanism for forcing down the opposite end of the knife, all substantially as described.

ARTHUR L. STANFORD.

In presence of—

ELIJAH STANFORD,
JOSEPH D. PLONIEN.
